UNITED STATES PATENT OFFICE.

JOHN A. JOHNSON, OF NEW YORK, N. Y.

HEAD FOR SPINNING CLOSURES ON BOTTLES, JARS, AND THE LIKE.

Application filed February 25, 1925. Serial No. 11,497.

To all whom it may concern:

Be it known that I, JOHN A. JOHNSON, a citizen of the United States, residing at Queens Borough, New York city, in the 5 county of Queens and State of New York, have invented certain new and useful Improvements in Heads for Spinning Closures on Bottles, Jars, and the like, of which the following is a specification.

10 My invention relates to heads for spinning caps or closures onto bottles or jars and the like and it is my object to produce mechanism in which the spinning disks are out of contact with the cap at all times, except while they are actually spinning the metal under the lip on the mouth of the bottle or jar and in which the spinning disks are positively moved and held out of such contact after the spinning operation is complete and before the top sealing pressure on the cap is removed. A further object is the construction of the head in such a manner that undue pressures will be relieved before the bottle or jar can break and to provide sufficient tolerance to permit the capping of bottles or jars whose dimensions vary within permissible commercial limits.

Heretofore spinning heads have been so constructed that there is a tendency for the 20 bottle or jar to hang in the head after being capped and to be lifted with it. When this occurs in rotary machines, in which a plurality of heads travel in a circle, this hanging has resulted in centrifugal force 35 violently throwing the capped bottle or jar out of the machine to the injury of the operator or others.

In the drawing Fig. 1 is a front view of 40 my head showing the bottle support with a jar thereon; Fig. 2 a detail sectional view showing a portion of the head in its upward position with one of the spinning disks in its out or non-operative position; Fig. 3 a sectional view of the head in its downward position with the spinning disks in contact with a cap; Fig. 4 a bottom view of the head with one of the spinning disks removed; and Fig. 5 a detail view, partly in section, of the spinning disk mounting.

50 The head comprises a grooved block 1 in which a slide block 2 reciprocates, the latter being raised and lowered by any of the well known mechanisms. This slide block 2 has two forward extensions 3 and 4. A driving shaft 5 with a driving gear 6 thereon passes

through the extension 3 and has its lower bearing in the extension 4.

A sleeve 7 passes through the extension 4 and has its upper bearing in the extension 3. A pinion 8, narrower than the gear 6 is 60 secured to the sleeve and meshes with the gear 6. The lower end of this sleeve 7 opens out into a frame 9 carrying the spinning mechanism. Within the sleeve is a plunger 10 which passes through the upper extension 65 3 and has a stop 11 adapted to bear against the top of the extension 3 to limit its downward movement. A helical spring 12 surrounds the plunger 10 with its upper end bearing against the extension 3 and its lower 70 end bearing against a shoulder 13 on the plunger to exert a downward pressure on the plunger. Interposed between the plunger 10 and the inner face of the frame 9 is a thrust bearing 14 which is held in position by a spring 15, the upper end of which bears against the thrust bearing and the lower end against a shoulder on the plunger 10. On the lower end of the plunger is 75 a top sealing pressure disk 16 which bears against a cap on a bottle or jar to compress the gasket and effect a sealing pressure before the spinning takes place.

In the drawing I have illustrated a head 80 with three spinning disks but any number may be used. I will describe the construction and operation of one of these spinning disks as the others are identical with it.

A pair of lugs 17 and 18 are formed on the under side of the frame 9 at its outer edge. A block 19 is swingingly mounted between these lugs on a pin 20 passing through the block and secured to the lugs. This block 19 carries a stud 22 on which a spinning disk 23 may freely revolve, the stud being locked in place in the block by a set screw 25 entering a socket in the stud as best shown in Fig. 5. A spring 25 between the inner end of the block 19 and the under side of the frame 9 normally holds the spinning disk in its outward or inoperative position.

A ring 26 is vertically slidable on the frame 9 and the two are normally forced apart by a spring 27 between them. The upper face of this ring bears against the under side of the slide block 2. A pressure button 28 passes through the frame 9 and the ring 26, being limited in its downward movement by a stop 29 and held down by a spring 105 110

30 between the ring 26 and the head of the button. The buttons, passing through the ring and frame, cause the two to revolve together. The rounded nose of this button 5 bears against the outer end of the swinging block 19.

In operation the head is up as shown in Fig. 2, a bottle or jar *a* with a cap *b* having a plain cylindrical skirt, is placed loosely 10 thereon and the two are placed under the sealing head.

The shaft 5 is revolved in any desired manner causing the sleeve 7 to revolve at a high speed, but the plunger 10 and its attached parts remains stationary. The whole 15 head is then forced downward by any desired mechanism and the disk 16 bears against the top of the cap *b* to compress the gasket therein and to apply the top sealing pressure, the spring 12 compressing and allowing the plunger 10 to rise as the downward movement of the head continues.

While this is going on the frame 9 and its attached parts is rapidly revolving and 20 on the further downward movement of the head the spring 27 is compressed allowing the frame 9 and the ring 26 to approach one another, the ring 26 being prevented from rising by reason of its contact with the 25 under side of the slide block 2. The upward movement of the frame causes the buttons 28 to swing the blocks 19 inwardly until the spinning disks 23 contact with the skirt of the cap below the bead on the neck of the 30 bottle when they begin to revolve on their studs and as the frame and ring continue to approach they spin the metal of the cap under the bead on the bottle, any excess pressure being absorbed in the springs 30 which allow the buttons to move upwardly before sufficient pressure can be built up to break the glass. This compensates also for any irregularities in the sizes of the bottle 40 or jar necks. As the head rises the spring 27 causes the frame 9 and the ring 26 to recede from one another and the springs 25 swing the blocks outwardly thereby positively moving the spinning disks clear of the bottle 45 or jar before the pressure on the plunger 10 is released. The final part of the upward movement of the head lifts the plunger 10 and its attached parts off the cap so that it is impossible for a bottle or jar to hang in the spinning devices and then be thrown 50 violently therefrom in a rotary capping machine.

The ball thrust bearing 14 reduces the friction between the stationary plunger 10 and the revolving sleeve 7 so that there is no 55 tendency of the former to revolve with the latter.

I claim:—

1. A head for spinning closures on containers comprising a slide block, a sleeve 60 vertically slidable therein and terminating

in its lower end in a frame, means for revolving said sleeve, a block swingingly mounted in the lower part of said frame, a spinning disk revolvably mounted on said block and adapted to contact with a closure, 70 a ring on said frame between it and the block, yieldable means for normally separating the frame and ring, a button mounted on said ring and adapted to bear against the outer end of the swinging block, a plunger mounted on the slide block within the sleeve, the lower end of which is adapted to bear on a closure top, and means on said plunger for exerting a sealing pressure on a closure. 75

2. A head for spinning closures on containers comprising a slide block, a sleeve vertically slidable therein and terminating at its lower end in a frame, means for revolving said sleeve, a block swingingly mounted in the lower part of said frame, a spinning disk revolvably mounted on said block and adapted to contact with a closure, 80 a ring on said frame between it and the block, yieldable means for normally separating the frame and ring, a button, yieldable vertically and mounted on said ring and adapted to contact with the outer end of the swinging block, a plunger mounted on said slide block within said sleeve the lower end of which is adapted to bear on a closure top and means on said plunger for exerting a sealing pressure on a closure. 85

3. A head for spinning closures on containers comprising a slide block, a sleeve vertically slidable therein and terminating at its lower end in a frame, means for revolving said sleeve, a block swingingly mounted in the lower part of said frame, a spinning disk revolvably mounted on said block and adapted to contact with a closure, 90 means for normally holding the swinging block and spinning disk in inoperative position away from a closure, a ring on said frame between it and the block, yieldable means for normally separating the frame and ring, a button mounted on said ring and adapted to bear on the outer end of the swinging block, a plunger mounted on said slide block within the sleeve the lower end of which is adapted to bear on a closure top and means for exerting a sealing pressure on a closure. 95

4. A head for spinning closures on containers comprising a slide block, upper and lower extensions thereon, a shaft in said extensions, a gear on said shaft, a sleeve in said extensions, a pinion on said sleeve meshing with the gear, said sleeve terminating at its lower end in a frame, a plurality of swinging blocks mounted on the lower part of said frame, a spinning disk revolvably mounted on each of said blocks, a spring between the inner end of each block and the frame, a ring between the frame and slide block, a spring between the frame and 100

ring normally holding them apart, a plurality of buttons slidably mounted on the ring and passing through the frame, the nose of each of which bears on the outer end of a swinging block, a spring on each of said buttons normally holding it down, a plunger within the sleeve and extending through the upper slide block extension and adapted to

bear on the top of a closure to apply a sealing pressure, and a spring surrounding said 10 plunger and bearing against it at one end and against the extension at the other.

In testimony whereof I have affixed my signature.

JOHN A. JOHNSON.
